CLAIM

The ornamental design for a handle, as shown and described.

DESCRIPTION

FIG. 1 is a perspective view of a handle showing my new design;

FIG. 2 is a front view thereof, a rear view being identical thereto;

FIG. 3 is a top view thereof;

FIG. 4 is a right side view thereof, a left side view being identical thereto; and,

FIG. 5 is a bottom view thereof.

The bore holes shown in broken lines in FIG. 5 are provided for illustration only and form no part of the claimed design.
